DESIGN FOR A HAT BLOCK

Abraham Solosko, Chicago, Ill.

Application July 21, 1939, Serial No. 86,166

Term of patent 3½ years

To all whom it may concern:

Be it known that I, Abraham Solosko, a citizen of the United States, residing at Chicago, in the county of Cook and State of Illinois, have invented a new, original, and ornamental Design for Hat Block, of which the following is a specification, reference being had to the accompanying drawing, forming part thereof.

Fig. 1 is a front view of a hat block showing my new design;

Fig. 2 is a side view of the hat block;
Fig. 3 is a plan view of the hat block; and
Fig. 4 is a rear view of the hat block.

I claim:

The ornamental design for a hat block, as shown.

ABRAHAM SOLOSKO.
